UNITED STATES PATENT OFFICE

110,635

DESIGN FOR A CLIP

Georges Albert Julien Bezault, Juvisy-sur-Orge,
France, assignor to Cartier, Societe Anonyme,
Paris, France, a company of France

Application September 1, 1937, Serial No. 71,418
In France March 22, 1937

Term of patent 7 years

To all whom it may concern:

Be it known that I, Georges Albert Julien Bezault, a citizen of the French Republic, residing at Juvisy-sur-Orge, Seine-and-Oise Department, France, have invented a new, original, and ornamental Design for a Clip, of which the following is a specification, reference being had to the accompanying drawing, forming part thereof.

I claim:

The ornamental design for a clip, substantially as shown.

GEORGES ALBERT JULIEN BEZAULT.
